(57) **CLAIM**

The ornamental design for a sample bag clip, as shown and described.

DESCRIPTION

FIG. 1 is a front view of a sample bag clip showing our new design in its closed position;

FIG. 2 is a front perspective view thereof in its opened position;

FIG. 3 is a front view thereof in its opened position;

FIG. 4 is a right side view thereof in its closed position;

FIG. 5 is a right side view thereof in its closed position; and,

FIG. 6 is a top plan view thereof.

The broken line showing of a hinge mechanism in FIGS. 3, 4, and 5 is included for the purpose of illustrating environment and forms no part of the claimed design. The rear and bottom views are not shown and are not part of the claimed design.
